POTENTIAL TRANSFORMER

Franklin R. D'Entremont, Dover, N.H., assignor to
General Electric Company, a corporation of New
York

Filed July 22, 1966, Ser. No. 3,187

Term of patent 14 years

(Cl. D26—15)

FIGURE 1 is a perspective view of a potential transformer showing my new design;

FIGURE 2 is a top plan view of the transformer;

FIGURE 3 is a side view thereof; and

FIGURE 4 is an end view thereof.

I claim:

The ornamental design for a potential transformer, as shown.
